TIRE

Robert A. Stella, Mogadore, and James W. Stiffler, Tallmadge, Ohio, assignors to The Goodyear Tire & Rubber Company, Akron, Ohio

Filed Dec. 1, 1971, Ser. No. 203,944

Term of patent 14 years

Int. Cl. D12—15
U.S. Cl. D90—20 R

The figure is a perspective view of a tire showing our new design, it being understood that the design is repeated throughout the circumference of the tire, the opposite side being substantially the same as that shown.

We claim:

The ornamental design for a tire, substantially as shown and described.
